MARINE EDIFICE

Ross White, Houston, Tex., assignor to Brown and Root, Inc., Houston, Tex., a corporation of Texas

Application August 4, 1947, Serial No. 765,857

1 Claim. (Cl. 214—12)

1

This invention pertains to a marine edifice suitable for a base of operations, particularly marine construction operations such as offshore drilling for petroleum.

The principal object of the invention is to make it possible to carry on such operations during all types of weather excepting hurricanes and storms of like severity.

It is a further object of the invention to minimize the dangers to life and property of such operations.

A still further object of the invention is to reduce the cost of such operations.

Briefly described, the invention contemplates the provision of a small stationary platform supported out of the water on piling, from which platform operations such as drilling an under water well hole may be carried on. At a considerable distance from the platform a tower is erected out of the water and between this tower and a similar tower mounted on or near the main platform there will be mounted a highline on which an ordinary cable car can be suspended and operated to move back and forth between the towers and up and down beneath the highline. Between the main platform and the tail tower for the highline a large floating vessel is moored. Preferably, the vessel is moored with its bow in the direction of the prevailing wind, the mooring being adjustable from the vessel to take care of minor shifts in the wind so that the vessel can always be made to face directly into the wind. The vessel should be of such length that it will span the distance between wave crests of any ordinary waves which are encountered in the area where the construction is to be carried on. By the term ordinary waves is meant such waves as occur during ordinary weather, rough as well as calm, but excluding hurricanes and storms of like severity. Usually such waves will not be over two hundred feet long.

On board the floating vessel are carried all the necessary supplies and personnel needed for carrying on the marine construction. Both men and materials are transferred to the working platform as needed by means of the cable car. Certain fluid materials such as water, fuel oil and drilling mud may be transferred from the floating vessel to the main platform by means of under-water pipes connected to the vessel by flexible risers.

The advantages of the invention as just described can most easily be pointed out by comparison with another proposed form of operating base for offshore drilling comprising a fixed platform which is large enough to carry not only

the drilling rig but also a substantial quantity of materials and equipment such as pipe and mud and also to provide a permanent living quarters for the workmen. Such an arrangement has a high initial cost and a low salvage value when the drilling operation is completed. In addition there is a great risk of loss or serious damage to the platform and the equipment thereon during conditions of bad weather, for the entire platform being immobile is exposed to the full force of the wind and sea at all times. Offshore drilling conducted on even the largest fixed platform which can be economically constructed is not a self-sufficient operation and the platform must be continually supplied with pipe, drilling mud, fuel oil, and provisions from shore by small boats or barges. This supply may be interrupted during rough weather which makes it dangerous to personnel and equipment for small barges to go alongside the platform for unloading. A third disadvantage of the fixed platform system is the personnel problem. Not only are the personnel exposed to danger by being unable to leave the site of drilling operations in case of severe storm or hurricane but their quarters for living are necessarily cramped. There is the further problem of making suitable disposition of off-shift personnel in a manner so as not to affect the efficiency nor morale of the men who are working.

All three disadvantages of the large fixed platform system of offshore drilling are overcome by the present invention; thus since only a small platform is provided of just sufficient size to accommodate the derrick, draw works and high pressure pumps, together with a small supply of equipment and materials, it will not have nearly the high initial cost of a large platform nor will there be as great a problem of salvaging the platform when the drilling operation has been completed and it is desired to move the platform elsewhere. Since the structure need not carry such a heavy weight of supplies a minimum of lateral bracing can be used so as to reduce the area exposed to violent wave action. Only a single deck need be provided, which can be arranged in panels for rapid erection and dismantling. All large stores of equipment and all housing and messing facilities and personnel will be provided on the floating vessel which may easily be moved from one location to another when drilling operations have been completed. In case of severe storm or hurricane the vessel can be removed to a safer position. Such supplies and material as are needed on the platform can easily be transferred from the floating vessel to the

platform by means of the cable car. This can be accomplished even in rough weather since a large vessel will have but a small rise and fall due to the fact that it bridges between waves rather than rides on an individual wave.

For a detailed description of a preferred embodiment of the invention reference will be had to the accompanying drawings in which—

Figure 1 is an elevation of a marine edifice according to the invention, and

Figure 2 is a plan view thereof.

Referring to Figure 1 there is shown a platform 10 supported on piling 11. The piling is driven or otherwise placed into the ground beneath the floor 12 of the body of water 13. Light cross braces such as that indicated at 14 may be used to tie the piles together. Where the platform 10 is to be used as a base from which to carry on drilling operations a derrick 15 may be erected on the platform 10. At one side of the platform 10 there is erected a tower 16.

At a considerable distance from the platform 10, perhaps 500 feet more or less, a second tower 17 is erected on piles 18 which, like the piles 11, are placed into the ground beneath the floor of the body of water 13. In some cases where drilling operations are to be carried on fairly near to the shoreline the tower 17 may be erected on dry land but in the usual case both towers will be over water.

Between the towers 16 and 17 there is placed a cable way of known construction which may comprise, for example, a main supporting cable 20 fixed each end to opposite towers. A carriage 21 is supported on wheels which run on the cable 20. The carriage 21 can be moved back and forth along the cable between the towers 16 and 17 by means of a traversing cable 22 which passes around sheaves at the tops of the towers 16 and 17 and the ends of which are both connected to the carriage 21. A bight of the cable at tower 16 passes around reversible winch 23. A skip 24 is supported on a hook depending from sheave 25 which in turn is supported from the carriage 21 by a hoist line 26 fixed at one end to the carriage 21 and passing around the sheave 25 and a pulley on the carriage 21. The other end of the hoist line 26 passes through guides 27 suspended from the main cable 20 and thence over a sheave at the top of tower 17 down to another reversible winch 28.

Beneath the cable way there is moored a floating vessel 30. Between the vessel 30 and the platform 10 there are suitable conduits for fluid materials, each of which includes a flexible hose 31 connected to an underwater pipe 32 laid on the floor 12 and a riser 33. These fluid conduits are shown in plan view in Figure 2 where by way of example there are shown three conduits 34, 35 and 36 for carrying low pressure mud, fuel oil, and water from the vessel 30 to the platform 10 where drilling operations are carried on.

Figure 2 illustrates a preferred method of mooring the vessel 30. The vessel is connected by 4 cables 41, 42, 43 and 44 to spring buoys 45, 46, 47 and 48. The spring buoys comprise merely large buoys connected by very heavy chains 49, 50, 51 and 52 to heavy anchors such as that shown at 53 which preferably is of the type known as the Eell anchor which has two long angularly disposed tapered flukes extending backward from the anchor stem. The buoys 45, 46, 47 and 48, being of large size will normally remain out of water and the heavy chains con-

necting them to the Eell anchors will assume the form of a catenary. In case of a sudden force applied to the vessel by wind or wave the spring buoys will act as shock absorbers, reducing the tension on the cables 41, 42, 43 and 44. In such case the buoys will be pulled slightly under water and the chains connecting them to the anchors will straighten out.

The cables 41, 42, 43 and 44 pass through rotary chocks and thence to power winches such as that shown at 54. By adjusting the lengths of the cables with the winches the vessel 30 can be turned to any desired position within limitations depending on the geometry of the particular mooring. By this means the vessel 30 can be turned so that its longitudinal or streamline axis is directed into the wind. The mean position of the ship as determined by the positions of the four anchors should be that of the prevailing wind and the range of change of direction of the vessel should be sufficient to care for normal variations of the usual wind direction.

The vessel 30 should be of small beam compared to the distance between the platform 10 and the tower 17 to minimize the possibility of the vessel being carried over against one of them in a storm. In addition, although the ship is of small beam compared to its length the length of the vessel should be substantially less than the distance between the platform 10 and tower 17 to minimize the possibility of one end of the vessel swinging over against the platform in case it breaks loose from its moorings at one end. For example, as shown in the drawing, the vessel 30 is of a length equal to approximately two-thirds the distance between the platform 10 and the tower 17. Since the platform 10 is the location of the construction work to be performed, e. g., oil well drilling, it is particularly important that the vessel never be allowed to contact the platform 10 and for this reason additional moorings may be provided. As shown in Figure 2 these side moorings comprise cables 55, 56 which are connected to spring buoys 57, 58 similar to the spring buoys of the main 4-point mooring, each being provided with a heavy chain and Eell anchor as shown at 59 and 60. The length and tension of the cables 55 and 56 can be changed by means of a power winch 61 to which either of the cables can be connected through a suitable block and tackle 62 and stationary pulley 63. For additional stability the usual bow and stern anchors 64 and 65 carried on chain 66 and cable 67 respectively, can be used.

The towers 16 and 17 are preferably disposed so that a line drawn between them is at right angles to the direction of the usual wind and sea so that when the vessel 30 is moored therebetween heading into the wind the cable 20 will run athwart ship thereof. While it is usually preferable to place the tower 16 on the platform 10 or immediately adjacent thereto so that the cableway operator in the tower 16 can be in immediate communication with the workmen on the platform 10 it is within the purview of the invention that the tower can be placed at some distance from the platform 10. It is only necessary that the cableway pass over the top of the platform 10.

There is also some latitude with respect to the point along the length of the vessel 30 at which the cableway crosses for as long as the vessel 30 is of considerable length compared to the crest-to-crest wave length of the rough sea normally encountered there will be very little pitch. How-

ever, it is preferable that the cableway 20 cross the vessel 30 directly amidship, in which case the pitch of the vessel will have practically no effect whatsoever and the only motion noticeable will be a slight rise and fall and also perhaps a slight roll if the vessel is not headed directly into the wind. It is because of this comparative stability of the amidship section of a large vessel that it is possible to transfer men and materials from the skip 24 to the vessel 30 even in relatively rough weather.

In use of the marine edifice previously described the men will be housed on the vessel 30 and all the materials required for a normal drilling operation to the expected depth of the well will also be carried on the vessel. On the platform 10 there will be carried only enough men to operate the drilling rig and the cableway. Pipe, casing, and other materials will be transferred to the platform 10 from the vessel 30 as needed. Fluid materials will be pumped to the platform through the underwater conduits. In case of storm all the men can be removed from the platform to the vessel 30 and if a hurricane or other severe storm is predicted the vessel 30 may be disconnected from its moorings and taken to a place of shelter. For this purpose the connections between the cables 41, 42, 43 and 44 and the spring buoys is preferably made of a quick attachable-detachable type. The flexible hose for the fluid conduits are also disconnected from the vessel, blanked off and buoyed so that re-connection can be made after the storm is over. The vessel 30 is preferably self-propelled but may in some cases be merely a barge which is towed to and from location with a tug.

While a preferred embodiment of the invention has been shown and described, many modifications thereof can be made by one skilled in the art without departing from the spirit of the invention and it is intended to cover by Letters Patent all forms of the invention falling within the scope of the appended claim.

I claim:

Apparatus for conducting offshore marine operations comprising a structure built completely off shore on the marine floor and rising above water, a working platform supported above water on said structure, an elongated vessel, means for elastically mooring the vessel to the marine floor whereby the vessel can move without breaking loose its mooring but is constantly restrained from motion, means on said vessel for adjusting said mooring means to keep the vessel headed into the wind whereby to minimize rolling of the vessel, said vessel having a length of about two hundred feet at least whereby the vessel can span the crests of the longest calm and normal rough weather ocean waves to minimize rise and fall and pitching of the vessel, a pair

60

of structures built on the marine floor and rising above water, two towers supported one on each of said pair of structures, said tower supporting structures being spaced apart with said platform 5 and the amidships section of the vessel in between and in line therewith, the distance from the amidships section of the vessel to the nearest one of said platform and tower supporting structures being greater than half the length of the 10 vessel whereby as the vessel is turned to head into the wind it will always be clear of said structures, said line between the tower supporting structures being perpendicular to the direction of the prevailing wind whereby the vessel 15 when headed into the wind will as nearly as possible always be at right angles to said line between said pair of tower supporting structures with its narrowest part in the direction of the line between said pair of structures and its bow 20 and stern far removed from said pair of structures and said platform supporting structure, a high line supported on said towers running over the platform and over the amidships section of the vessel where the vessel is most nearly stationary, a skip supported on the high line, and means to move the skip up and down and along the high line between the vessel and platform whereby men and materials can be conveyed between said vessel and working platform in all 25 weather except severe storms and hurricanes, said towers supporting the highline above the highest point of the vessel whereby the vessel is entirely clear thereof and can be moved freely therebeneath when the skip is raised away therefrom, said mooring means being releasable whereby the vessel can be moved out of the path of a storm, said structures for supporting said platform and towers being of openwork construction to allow high velocity fluids to pass therethrough without damage to said structures.
